(57) CLAIM

The ornamental design for a patient-monitor housing, as shown and described.

DESCRIPTION

FIG. 1 is a top perspective view of the patient-monitor housing according to an embodiment of the present invention; FIG. 2 is a front view of the patient-monitor housing shown in FIG. 1;

FIG. 3 is a top view of the patient-monitor housing shown in FIG. 1;

FIG. 4 is a bottom view of the patient-monitor housing shown in FIG. 1;

FIG. 5 is a left-side view of the patient-monitor housing shown in FIG. 1;

FIG. 6 is a right-side view of the patient-monitor housing shown in FIG. 1; and,

FIG. 7 is a rear view of the patient-monitor housing shown in FIG. 1.

The broken lines shown herein are for illustrative purposes only and form no part of the claimed design.
